UNITED STATES PATENT OFFICE

THOMAS H. SLY, OF DUNMORE, SCRANTON, PENNSYLVANIA

SAND SCOOP

Application filed July 12, 1927. Serial No. 205,257.

This invention relates to improvements in scoops, and more specifically to reversible scoops.

The principal object of this invention is to provide a scoop which may be turned upside down as soon as the underside becomes worn or broken.

Another object is to provide teeth and scraper edges which may be readily replaced.

Still another object is to provide a scoop of such particular shape and construction as to first loosen dirt, stones and other obstructions, and efficiently collect the same and remove to the desired location.

Other objects will be shown in the specification and drawings.

In the drawings:

Figure 1 is a top plan of the scoop; Figure 2 is a side elevation of the scoop shown in Figure 1; and,

Figure 3 is a section taken along line 3—3 of Figure 1.

In the drawings similar parts are designated by like numerals.

Numeral 1 designates a scoop having five sides. Each side is composed of three plates, the upper plate or edge being designated by numeral 2, the middle plate by numeral 3 and the bottom plate or edge by numeral 4. Plates 2 and 4 are detachably secured to the middle plate 3 which forms the frame by bolts 6'. On the lower and upper edges 4 and 2 respectively of the three rear sides, 35 are mounted teeth 5 held in place by bolts 6. The plates 2 and 4 are secured to the middle plate 3 at an angle so as to more readily scrape the dirt and hold the same. Connecting the two front sides of the scoop 40 is a brace rod 7. Attached to the middle plates of the two front sides are chains 8 connected by a ring 9 to which in turn is attached a cable 10. To the rear of the scoop is attached a cable 11.

The scoop when ready for use will take

the form of an open five sided figure having the two outermost sides parallel and opposite and two other sides connected to the parallel sides and inclined inwardly with a fifth plate connected to the two inwardly 50 inclined sides to form the rearmost portion of the scoop and substantially parallel to the brace rod.

As actually used, the motive power is attached to cable 10, the scoop being drawn over the surface from which dirt is to be removed. The teeth 5 dig into the ground acting in the manner of a harrow, loosening the dirt and dislodging stones and similar obstacles. The dirt is then gathered on the 60 lower edge of the scoop and accumulates as the scoop is moved forward. Should the lower edge of the scoop become damaged in any way, the scoop may be reversed and the upper edge used until the lower side can be 65 repaired. It is also apparent that this feature will practically give the scoop a double life. It is also apparent that should any of the teeth become broken or lost or scraper plates damaged that they may very readily 70 be replaced.

Having described my invention, what I claim as new and novel is:

1. A scoop comprising a five sided frame member two sides of said frame arranged 75 parallel and spaced apart, two sides adjacent the first two inclined inwardly at an angle thereto and the fifth side connecting the angularly positioned sides and substantially perpendicular to the parallel sides, 80 said frame having its upper and lower edges inclined inwardly at an angle, scraper plates removably secured to the opposite inclined edges of each side of the frame member at an angle thereto, whereby said frame and 85 scraper members constitute a scoop of channel cross section.

2. The structure of claim 1 in which the frame member is positioned with the main plane of each side perpendicular to a com- 90

mon plane with a spacer rod positioned between the parallel sides of the frame member adjacent their free ends and draft coupling means secured to the free ends of the frame member.

3. The structure of claim 1 with teeth removably secured to the scraper plates, said teeth all arranged substantially parallel with each other and with the parallel frame members.

10 In testimony whereof I affix my signature.

THOMAS H. SLY.
